UNITED STATES PATENT OFFICE

EDWARD H. SCHANE, OF CLEVELAND, OHIO, ASSIGNOR TO THE FANNER MANUFACTURING COMPANY, OF CLEVELAND, OHIO, A CORPORATION OF OHIO

AWNNG SUPPORT

Application filed September 24, 1928. Serial No. 308,113.

This invention relates to a support which is adapted to be used in connection with the hanging of awnings, and in use is adapted to be attached to a portion of the building 5 on which the awning is to be mounted and serve as a support and clamp for the top rod of the awning as well as provide a support for the pulleys which receive the rope by which the awning is raised and lowered.

10 The object of the invention is to provide a clamp formed in two parts with the hooks for supporting the pulleys carried by the movable clamping part.

A further object is to provide a form of 15 support which is particularly adapted for use in connection with awnings of the roll-up type, which clamp may be so mounted upon the building that the pulleys will hang upon the inside of the awning and thus present 20 a more finished appearance to the awning when viewed from the outside of the building.

Reference should be had to the accompanying drawings forming a part of this 25 specification, in which

Figure 1 is a front elevation.

Figure 2 is a side elevation.

Figure 3 is a sectional elevation.

Figure 4 is a front elevation of a portion of 30 the support.

Figure 5 is a front elevation of a modified form.

Figure 6 is a side elevation of a modified form.

35 Figure 7 is a top plan view of a portion of the support of the modified form.

Figure 8 is a front elevation of a portion of the support of the modified form, and

Figure 9 is a top plan view of the showing 40 in Fig. 8.

It is customary in supporting awnings to provide the top portion of the awning with a suitable metal rod which is attached to the top portion of the awning in any suitable manner. This iron rod is supported upon the building upon which the awning is to be mounted by suitable supports, and the present invention is directed to a support of this character.

50 One type of awning in use may be termed

the roll-up type, in which the awning proper is at the top portion thereof provided with a suitable rod attached to the awning, and the lower portion is provided with a cylindrical roll member, and suitable ropes are provided which are reeved through pulleys at the upper portion of the awning, so that the awning may be rolled up upon the lower cylindrical member and conveniently unwound from the cylindrical member when desired.

With such types of awnings it is desirable to have a type of support for the upper rod of the awning of such character that the pulleys, carried by the support are upon the inside of the awning, thus presenting a more finished appearance to the awning when viewed from the exterior of the building. Such a type of support is illustrated in Figures 1 to 4 of the drawing.

Such a support comprises a base portion 1, which is provided with suitable openings 2 adapted to receive screws or other suitable members, so that the base portion 1 may be attached to the building. The base portion is provided with an outwardly extending threaded pin 3 and at its lower portion has an extension 4 which is formed with a rounded surface 5.

The clamping member has a centrally disposed portion 6 provided with an opening 7 which is adapted to be inserted over the pin 3. The portion 6, is provided upon the rear surface thereof, with a rounded part 7^a which is oppositely disposed with respect to the rounded portion 5 when the member 6 is mounted upon the pin 3. The clamping action is obtained by means of a wing nut 8 which is adapted to be threaded upon the pin 3 to thereby force the member 6 toward the base member 1.

In Figure 1 there is shown in dotted lines a rod 9 which may be described as a rod such as it attached to the upper part of an awning. This rod member 9 is adapted to be inserted between the rounded portions 5 and 7, so that as the wing nut 8 is turned to force the member 6 inwardly the rod is securely clamped between the base portion 1 and the member 6.

100 It will be observed that the construction

usually described provides considerable latitude as to the possible diameter of rod which may be clamped between the base member 1 and the member 6. In fact, a clamp of the 5 construction disclosed is capable of receiving all sizes of rods which are customarily used in connection with awnings. Therefore, a clamp of the construction which has been described may be said to be universal in its 10 use with respect to the various sizes of awnings rods. Therefore, it is not necessary to provide various sizes of clamps for different sizes of awning rods.

Depending from the member 6 are a plurality of hook members 10, these hook members being provided with outward extensions 11 which prevent accidental dislodgment of the eyes of the pulleys which are customarily used in connection with awnings and which 20 are represented at 12.

It will be seen that when a support of the construction which has been described is used in connection with a roll-up type of awning, the base member of the support will be mounted upon the inside of a molding, so that the 25 hooks 10 and pulleys 12 supported thereby will be upon the inside of the awning and, therefore, will not be exposed upon the outside of the awning, which would considerably detract from the appearance thereof.

In the form of support shown in Figures 5 to 9 inclusive the base member is indicated by the reference character 13, and is more particularly shown in Figure 7. The base member has suitable openings, as indicated 35 at 14, which are adapted to receive securing means by which the base may be attached to a building. The base is provided with an outwardly extending portion 15 which, upon 40 the top and bottom portions thereof, is provided with a reentrant recess, as shown at 16 in Figure 7, and at the forward part of the extension 15 there is a depending flange 17 which is provided with a rounded surface 18.

The clamping member 19 is more particularly shown in Figure 8, and at its upper portion has an extension with a rounded top part 20. The member 19 is also provided with an extended threaded pin 20. The lower 50 portion of the member 19 has a ridge 21 and the portion of the member 19 adjacent the ridge 21 is provided with a rounded surface 22, as shown in Figure 6. When the member 19 is assembled with respect to the member 15, as shown in Figure 6, the rounded portions 22 and 18 are oppositely disposed with respect to each other and are adapted to receive the usual awning rod 9.

At the lower portion of the member 19 60 there are depending hook portions 23, which are adapted to receive the usual pulleys 12.

When the base member 1 and the member 19 are assembled, the pin 20 extends through a suitable opening formed in the extension 65 15, and the portion 20 of the member 19 rests

upon the extension 15, thereby forming, in effect, a support for the member 19. It will be observed that due to the recesses 16, which have before been described, the member 19 is movable with respect to the member 15.

The clamping action is obtained by the use of a wing nut 24, which is threaded upon the pin 20. The wing nut abuts against the extension 15 and so draws the member 19 forward. When a rod 9 is mounted so as to 70 cooperate with rounded surfaces 18 and 22, such rod will be clamped in position as the wing nut is turned upon the pin 20. It will be seen that, due to the construction of those 75 portions of the clamp which receive the awning rod 9, that rods of various diameters 80 may be accommodated by the clamping members so that the support becomes universal and is adapted to receive all the various sizes of awning rods which are customarily used in connection with awnings.

It will be noted that the hooks 23 are carried by the movable member of the supporting clamp and are so positioned that the ends of the hooks will always be adjacent to the 90 rod 9 which is associated with the clamp. The arrangement is such that the ends of the eyes are sufficiently close to the rod 9 so that the eyes of the pulleys cannot be dislodged 95 from their hooks, and this will be true regardless of the size of awning rod which is associated with the support.

Due to the fact that the member 19 extends into the recesses 16 formed in the top portion and bottom portion of the extension 100 15, the member 19 cannot turn with respect to the extension 15 except to a very limited extent.

In both forms of the awning supporting device which have been described the hook 105 supports for the pulleys are carried by the movable member of the clamp support.

Obviously modifications of the precise structure which has been shown and described 110 may be made without departing from the spirit of the invention.

Having thus described my invention what I claim is:

1. A support and clamp of the character described, comprising a base portion adapted 115 to be attached to a fixed support, a movable member associated with said base member and having portions adapted to receive a rod to be clamped, a nut cooperating with the base member and the movable member and pulley hooks carried by the movable member.

2. A support and clamp of the character described, comprising a base member and a movable member, one of said members being 120 provided with a threaded extension, a nut mounted upon the threaded extension and adapted to move the movable member with respect to the base member, cooperating means upon the said members adapted to receive a rod to be clamped between them,

the movable member being provided with hooks for the reception of pulleys.

3. A support and clamp of the character described, comprising a base member and a movable member supported upon the base member, each of said members being provided with cooperating clamping portions, means for effecting a clamping action between the said clamping portions of the base and movable member, and pulley hooks carried by the movable member.

In testimony whereof, I hereunto affix my signature.

EDWARD H. SCHANE.
